UNITED STATES PATENT OFFICE

153,419

DESIGN FOR A TOE STOP BRACKET FOR ROLLER SKATES

Joseph M. Dabrow, New York, N. Y.

Application December 31, 1946, Serial No. 135,861

Term of patent 7 years

(Cl. D34—14)

To all whom it may concern:

Be it known that I, Joseph M. Dabrow, a citizen of the United States, residing at New York city, in the county of Kings and State of New York, have invented a new, original, and ornamental Design for a Toe Stop Bracket for Roller Skates, of which the following is a specification, reference being had to the accompanying drawing, forming a part thereof.

Fig. 1 is a side elevation of a toe stop bracket for roller skates, showing my new design.

Fig. 2 is a top plan view thereof.

Fig. 3 is a bottom plan view thereof.

Fig. 4 is a front end view thereof.

Fig. 5 is a sectional view taken on line 5—5 of Fig. 2.

I claim:

The ornamental design for a toe stop bracket for roller skates, substantially as shown.

JOSEPH M. DABROW.
